(57) **CLAIM**

I claim the ornamental design for a combination toothbrush and tongue scraper, as shown and described.

DESCRIPTION

FIG. 1 is a front perspective view of an embodiment of a combination toothbrush and tongue scraper;

FIG. 2 is a back perspective view thereof;

FIG. 3 is a front elevation view thereof;

FIG. 4 is a back elevation view thereof;

FIG. 5 is a first side elevation view thereof;

FIG. 6 is a second side elevation view thereof;

FIG. 7 is a first end view thereof; and,

FIG. 8 is a second end view thereof.

The broken lines, where shown, are for purposes of illustrating unclaimed portions that form no part of the claimed design. The space between the break lines also forms no part of the claimed design.

1 Claim, 7 Drawing Sheets
